UNITED STATES PATENT OFFICE.

JUAN D. JARRIJOU, OF BARCELONA, SPAIN, ASSIGNOR TO CHEMISCHE FABRIK TROISDORF DR. HÜLSBERG & SEILER, OF OBERLAR, NEAR TROISDORF, GERMANY.

LUBRICATING DEVICE.

1,104,901.

Specification of Letters Patent. Patented July 28, 1914.

Application filed March 21, 1912. Serial No. 685,182.

To all whom it may concern:

Be it known that I, JUAN D. JARRIJOU, a citizen of France, residing at Calle de Sepúlveda No. 187, Barcelona, Spain, have 5 invented certain new and useful Improvements in Lubricating Devices, of which the following is a specification.

The present invention relates to a method and an arrangement for lubricating both 10 stationary and oscillating or otherwise moving machine parts with consistent grease by means of which the quantity of grease intended for each respective part may be easily regulated. For this object a grease 15 press is employed, which will feed the grease and force it through stationary and movable pipes into the bearings and the like to be lubricated. This method can also be employed for the highest speeds and can be 20 regulated.

The present invention is exemplified in the accompanying drawings.

Figure 1 is a marine engine fitted with the new lubricating arrangement. The arrangement 25 comprises a grease feed press and a pipe system proceeding therefrom and consisting of rigid and articulated pipes adapted to conduct the grease to several parts to be lubricated. Figs. 2 to 9 are enlarged views of details of joints in the apparatus shown in Fig. 1. Fig. 10 illustrates another constructional form, in which the grease which is fed by the grease press enters into a distributor, whence it is conducted through oscillating and slidable pipes to the parts to be lubricated. Figs. 11, 12, and 13 are enlarged views of details of Fig. 10. Fig. 14 is another constructional form, the distributor being here fitted to 30 the crosshead of the engine and being manually regulable and adjustable from a stationary point. Figs. 15-20 are enlarged views of details of Fig. 14. Fig. 21 is a modification of the arrangement shown in Fig. 14. Figs. 22 and 23 are enlarged views 45 of details of Fig. 21.

In the arrangement according to Fig. 21 the distributor is likewise fitted to the cross-head; the grease is fed through the hollow 50 spindle which serves to adjust the distributor. The other figures show details of the various members.

In Fig. 1 the numeral 1 indicates a grease press or mechanical lubricator, which is directly driven by the steam engine. This

grease press will force the grease through the stationary pipe 2 to the joint 3 which is attached to the frame of the engine. From here the grease passes through pipe 4, which is connected at 5 by means of a movable 60 joint to the pipe 6, and the latter terminates in the movable joint 7 on the pin of the connecting rod. From here the grease proceeds through the pipe secured to the connecting rod, to the crank pin 9. At the same time 65 the grease will pass through the pipe 10 branched off pipe 2 to the main bearings of the crank shaft 11.

Fig. 2 is a section through the axis of the joint 3 in Fig. 1; Fig. 3 is a section on the line III—III in Fig. 2 and Fig. 4 is an outside view of the same joint. The joint consists of the body member 12, which has a base or flange, by means of which it is secured to the frame of the engine. Into the 70 mouth 13 is secured the pipe 2, through which the grease is forced. On the body 12 is rotatably fitted by means of a ball-bearing 17 the part 14. The joint between body 12 and part 14 is rendered tight by means of a 75 stuffing box 15. The part 14 communicates with pipe 4, through which the grease is conducted to the movable joint 5. In order to prevent the part 14 falling out or the balls 17 becoming shifted from their seat 80 when the packing in the stuffing box 15 is being renewed, the part 14 has a pin-shaped extension 16, which is screwed into the body 12 so that the thread will allow a comparatively wide range from the oscillations 85 of the pipe 14; the only object of this screwed pin is to prevent the pipe 14 from falling out when the stuffing box is unscrewed.

The Figs. 5 to 7 illustrate the movable 90 joint 5; Fig. 5 is a longitudinal section, Fig. 6 is a section on the line II—II in Fig. 5 and Fig. 7 is an outside view of the joint. This joint consists of the body 18 into the extension 19 of which is fitted the pipe 4. The 100 joint furthermore comprises the part 20 into the mouth of which is fitted the pipe 6. The part 20 is secured to the body 18 in the same manner as has been described with reference to the Figs. 2-4, namely by means 105 of a ball bearing 22, a stuffing box 21 and a threaded pin-extension 23.

The movable joint 7, which is shown in Figs. 8 and 9 in axial section and outside view respectively comprises the body 24 110

screwed to the pin 25 of the connecting rod, and an extension 26 into which the pipe 8 is fitted. On this body 24 is fitted by means of the ball-bearing 28 the top part 27, which 5 has a branched-off extension, to which the pipe 6 conducting the grease is fitted. A stuffing box 29 is provided to avoid any loss or leakage of grease, as it will produce a tight joint between the parts 24 and 27. A 10 threaded spindle 30 which is screwed into the part 27 extends through the parts 24; this spindle is operated by means of a hand-wheel 33 on its outer end and terminates below in form of a valve head 37, which will 15 control at will the passage of the grease into the passage. This passage will conduct the grease into the bearings of the connecting rod pin.

In the constructional form shown in Fig. 20 10 the grease is not conducted from the grease press directly and through a system of articulated pipes to the bearings to be lubricated, but proceeds from the press to a stationary distributor, whence it passes 25 through oscillating and slidable pipes to the oscillating or otherwise moving parts of the engine. The pipe 2 leading from the grease press conducts the grease to the distributor 34, which has a given number of oscillating 30 sockets 35, through which are passed slid- able pipes 36. Of these pipes the one con- ducts the grease to the joint 38, thence it is distributed over the working surfaces of the crossheads; through another of these 35 pipes the grease proceeds to the pin 39 of the connecting rod, and the third pipe con- ducts it to the joint 40 on the connecting rod, whence it proceeds through the pipe 41 to the crank-pin bearing. From pipe 2 40 is also branched off a pipe 42, which con- ducts the grease to the joint 43, whence it is distributed through pipes slidably fitted in sockets 44 (the same as in 35) over the working surfaces of the eccentrics. The 45 grease is lastly conducted through a station- ary pipe leading from the joint 43, to the crank-shaft bearings 11.

Figs. 11 and 12 illustrate the distributor 50 34 in its several parts; Fig. 11 is a section on the line XII—XII of Fig. 12 and the latter is a section on the line XI—XI in Fig. 11. This distributor consists of several sections 47 which are joined to each other by means of flanges, and the uppermost of 55 which communicates with the grease feed pipe 2, the lowermost section is provided with a base flange, with which it may be secured to a suitable part of the engine. In each of these sections 47 is fitted a pipe 48 60 the outside end of which terminates in form of a T in the socket tube 35. The pipe 48 is held in position by means of lock nuts 53 and the stuffing box 52; in its inner portion it is provided with a valve 49, which is con- 65 trolled by means of the handwheel 50. In

the socket 35 is slidably arranged the pipe 36 passing through stuffing boxes at both ends of the socket, and serving to conduct the grease to its destination. So for instance the grease will pass through the pipe 2 into the sectional chamber 47, through the valve opening 51 into the pipe 48, passes the valve 49 and into the socket tube 35 whence it enters the pipe 36 through the hole 37 in the latter, and finally reaches the respective bearing. It is evident that by simply operating the valve 49 by means of the hand-wheel 50 and without interfering with the grease press, the quantity of grease supplied to each bearing may be varied at will 70 from *nil* to a given maximum. 75

In Fig. 13 is shown in section the elbow 40, which is attached to the connecting rod. It consists of a body member 54 screwed to the connecting rod and having an extension 80 into which the pipe 41 is secured. On this body 54 is pivotally secured by means of the stuffing box 56 an intermediate member 55, which communicates with its outer leg with the pipe 36 leading to it from the distributor 34. 85

In the constructional form illustrated in Fig. 14 the distributor 59 is fitted to the crosshead of the steam engine and recipro- 90 cates with the same. It is, however, con- trolled by means of the handwheel 78 which is journaled on the engine frame. The grease proceeding from the grease press through pipe 2 is conducted to the distributor 59 through the oscillating socket 57 and the slidable pipe 58. From the distributor 59 proceed several pipes 69, 70, 71, 72, etc., which conduct the grease to the parts to be lubricated, so for instance 69 and 72 conduct the grease to the working 100 surfaces of the crosshead, 71 to the pin of the connecting rod and 70 to the movable joint 74, from which it passes through pipe 73 to the crank-pin bearing 9. By means of the handwheel 78, the bevel gears 77, 76, 110 the guide socket 75 and the rod 66 the distributor may be adjusted, so as to conduct the grease to each of the several parts to be lubricated, or to none at all or to all of them simultaneously. 115

The Figs. 15 to 20 illustrate the details of this arrangement. Fig. 15 is a section along the axis of the distributor 59; Fig. 16 is a section on the line XVI—XVI in Fig. 15, Fig. 17 is a constructional form of the gear 120 for controlling the distributor, and Fig. 18 is a front view of the handwheel 78. This distributor consists of the casing 59 having a flange 60 with which it is secured to the crosshead. From this casing proceed any 125 number of grease feed pipes. In the present instance five such feed pipes are shown. To the five connections are fitted the pipes 68 to 72, which conduct the grease to the vari- 130 ous parts to be lubricated. Within the cas-

ing 59 is arranged a conical member 61, which is held in position by means of the lock nuts 62 and is besides under action of the spring 63, so as to avoid all play between the cone and casing. The cone 61 terminates in the rod 66, which projects through the stuffing box 65 and may, by means of the gear shown in Fig. 17 be adjusted into seven different positions, namely in two more than the casing 59 has connections. This arrangement may of course be varied according to the requirements of the engine. The cone 61 is partly bored out in form of a duct 67 from which duct lead radially drilled holes 64 which form a communication between the central bore 67 and the several pipe connections. These holes 64 are disposed in such a manner, that in five of seven possible adjustments of the cone 61 they will make the duct 67 communicate with one of the pipes 68 to 72, in the sixth they will communicate with none of the pipes, and, lastly, in the seventh bring all pipes simultaneously into communication with the duct 67. The duct 67 communicates with the chamber 91. With the latter communicates pipe 58 through the stuffing box 90, the said pipe 58 conducting the grease coming from the grease press into the chamber 91. The rod 66, which is made of a square or any other suitable section extends through the guide socket 75, in which it can slide up and down, but not turn. By means of the handwheel 78 and the bevel gears 77, 76 the socket 75 can be given a rotary movement and thereby the cone 61 can be adjusted into the desired position according to the parts which are to be lubricated. For facilitating such adjustment the handwheel 78 which bears the names of the parts to be lubricated coöperates with a stationary index 79.

In Figs. 19 and 20 the movable joint 74 in Figs. 14 and 21 is shown in outside view and axial section respectively. This joint is attached to the pin of the connecting rod and differs somewhat from the afore described joint. It consists of the body 80 which is secured to the pin 25 of the connecting rod. To this body 80 is rotatably fitted by means of a ball bearing 83 a second member 82. On the body 80 is arranged a socket 81 by means of stuffing boxes into which is fitted the pipe 71, conducting the grease hither from the distributor. The grease proceeds through duct 92 and through hole 93 into the bore 94 in the body 80. Thence it proceeds through passage 32 to the respective bearing. The member 82 has an extension on one side to which is connected the pipe 70 coming from the distributor; in the face end of this member is rotatably fitted by means of a stuffing box the pipe 73, which conducts the grease to the crank pin bearing 9.

The constructional form shown in Fig. 21 employs a distributor 59 as illustrated in Figs. 15 and 16. But the grease is here conveyed to the distributor through a rod 86 instead of an articulated pipe. This rod 70 75 80 85 90 95 100 105 110 115 120 125 130 instead of an articulated pipe. This rod 86, which is also employed for regulating the distributor has in the present instance a central bore and communicates with the grease press by means of the pipe 84. The details of this constructional form are shown in Figs. 22 and 23, Fig. 22 showing an axial section and Fig. 23 being an outside view. The casing 59 of the distributor is also here provided with a flange 60 by which it is secured to the crosshead. It furthermore has a number of extensions to which are fitted the pipes leading to the various points to be lubricated. Also here the cone 61 is held in position by means of lock-nuts 62 and spring 63. The rod 86 extends throughout its whole length, and has a sectional shape which will admit of the cone 61 sliding along the rod but will not allow of its turning independently. The rod 86 is journaled with a ball-bearing 88 on the engine frame and can turn easily. The cavity 95 within the cone 61 communicates with the socket 85, into which the grease from the hollow rod 86 enters through the holes 87. The rod 86 communicates at its lower end by means of the moving joint 89, having a stuffing box, with the pipe 84, which supplies the grease from the grease press. The rotary movement is transmitted to the rod 86 in the hereinbefore described manner by means of a handwheel 78 and the bevel gears 76, 77.

I claim:

1. An arrangement for lubricating machine parts with consistent grease comprising a grease press, adapted to force the grease and a pipe system consisting of stationary and movable pipes and adapted to conduct the grease to the stationary and the moving machine parts, and a distributor attached to the machine, said distributor adapted to receive the grease from the grease press and conduct it through a system of rigid and articulated pipes to the respective parts to be lubricated, the said distributor consisting of a casing with a plurality of extensions in said casing a coöperating rotatable body, to conduct the grease to the machine parts.

2. An arrangement for lubricating machine parts with consistent grease comprising a grease press, adapted to force the grease and a pipe system consisting of stationary and movable pipes and adapted to conduct the grease to the stationary and the moving machine parts, and a distributor attached to the machine, said distributor adapted to receive the grease from the grease press and conduct it through a system of rigid and articulated pipes to the respective parts to be lubricated, the said distributor

consisting of a casing with a plurality of extensions in said casing a coöperating rotatable body, to conduct the grease to the machine parts, and means to vary the supply of grease supplied by said rotatable body.

3. An arrangement for lubricating machine parts with consistent grease comprising a grease press, adapted to force the 10 grease and a pipe system consisting of stationary and movable pipes and adapted to conduct the grease to the stationary and the moving machine parts, and a distributor attached to the machine, said distributor 15 adapted to receive the grease from the grease press and conduct it through a system of rigid and articulated pipes to the respective parts to be lubricated, the said distributor consisting of a casing with a 20 plurality of extensions, said casing having a coöperating conical rotatable body, bored

to conduct the grease to the machine parts according to the position to which the said conical body is adjusted, the said conical body comprising a rod guided in a socket 25 having such a shape as to allow of a sliding movement but prevent a rotary movement of the said rod, the said socket provided with a suitable gear and adapted to adjust the said conical body by means of said rod into the 30 desired rotated position, the pipe conducting the grease from the grease press to the distributor being secured at one end in a movable joint on the distributor and sliding at the other in an oscillating socket. 35

In testimony whereof I affix my signature in presence of two witnesses.

JUAN D. JARRIJOU.
